SUPPORT FRAME ASSEMBLY FOR TRAVELLING SWINGS OR SIMILAR ARTICLES

William R. Tomalinas, Jr., Wilkes-Barre, Pa., assignor to Roth American, Inc., Wilkes-Barre, Pa.

Filed Sept. 30, 1971, Ser. No. 185,483

Term of patent 14 years

Int. Cl. D21—03

U.S. Cl. D34—5 M

FIG1

FIG2

FIG3

FIG. 1 is a perspective view of a support frame assembly for travelling swings or similar articles showing my new design;

FIG. 2 is a side elevation thereof from the right side, the opposite side being a mirror image of the side shown;

FIG. 3 is an end elevation thereof from the forward end, the opposite end being a mirror image of the end shown.

A characteristic feature of my design for a support frame assembly for travelling swings or similar articles resides in a longitudinally extending support frame disposed within a transversely extending support frame.

I claim:

The ornamental design for a support frame assembly for travelling swings or similar articles, substantially as shown and described.
